United States Patent

Des. 238,112
Patented Dec. 16, 1975

238,112

UTILITY CASE

Ralph M. Nowak, Wilbraham, Mass., assignor to Tucker Cosco, Inc., Columbus, Ind.

Filed Dec. 26, 1973, Ser. No. 427,923

Term of patent 14 years

Int. Cl. D3—02

U.S. Cl. D87—1 R

Fig. 1

Fig. 2

Fig. 3

FIG. 1 is a side elevation of a utility case showing my new design;

FIG. 2 is an end elevation thereof; and

FIG. 3 is a top plan view thereof.

The side and end opposite those shown in FIGS. 1 and 2 are identical thereto.

I claim:

The ornamental design for a utility case, as shown and described.
